UNITED STATES PATENT OFFICE.

MICHAEL MILLER, OF GLENWOOD, IOWA.

TRESTLE.

SPECIFICATION forming part of Letters Patent No. 288,651, dated November 20, 1883.

Application filed March 26, 1883. (No. model.)

To all whom it may concern:

Be it known that I, MICHAEL MILLER, a citizen of the United States, residing at Glenwood, in the county of Mills and State of Iowa, have 5 invented a new and useful Trestle, of which the following is a specification.

My invention relates to improvements in trestles; and the objects of my invention are, first, to permit the trestle to be adjusted to 10 different heights and lengths, without changing any of its parts, by merely altering the relative position of the parts; second, to permit the trestle to be adjusted to different heights by changing the legs and then altering the 15 relative position of the parts; third, to permit trestles to be constructed with less timber and materials, and to permit their use without injury to the materials, and to preserve the full strength of the same; fourth, to permit 20 trestles to be constructed without nails or carpenter's work; fifth, to permit trestles to be conveniently taken apart without injury to any part thereof; sixth, to permit trestles to be easily put into small compass or space, 25 without injury thereto, for convenient removal, packing, transportation, or storage; seventh, to reduce the material requisite for the practical use of trestles; eighth, to secure immunity from accidents by the breaking or crushing 30 down of trestles. I attain these objects by the mechanism illustrated in the accompanying drawings, in which—

Figure 1 is a view in perspective of the several parts of the adjustable trestle combined 35 and set ready for use. It may be made of any desired length horizontally by changing the putlog or cross-piece D.

Fig. 2 is a view in perspective of the metallic trestle-head A, showing the slot to receive and 40 support the putlog or cross-piece D of the trestle; the pin-holes W, for fastening the putlog thereto, if desired; the pin or projection G to prevent the putlog working out of the slot; the shoulders O to meet the corresponding shoulders of the leg-sockets B; the slot H to receive the key C; the jaws M to support the putlog, and the circular hinge-bearing J to enter the adjustable leg-sockets B, and to be secured thereto by a pivot, if desired.

Fig. 3 is a perspective view of one of the

hinge leg-sockets of the trestle-head, showing the circular top fitted to receive the circular bearing of the part A, with slots i to receive the key C and hold the parts in adjustment; the shoulder O; the pin-hole K to admit the 55 fastening the leg L thereto, and the hook P to hold the chain N. (Shown in Fig. 5.)

Fig. 4 is a view in perspective of the key C, which works in the slots h i, which, raised to the top of the slot H, clears the upper part of 60 the leg-socket B, and which, when it rests in the slots i, also projects into the slots H and holds the leg-sockets B and the head A in adjustment.

Fig. 5 is a perspective view of the metallic 65 trestle-head A attached to the adjustable leg-sockets B by a pivot at J, showing the several parts lettered, as hereinbefore described. Near the lower end of the adjustable leg-sockets B are made hooks or projections P to 70 receive a chain, N, adjustable to any desired length, to hold the legs L at a given distance apart, such distance being ascertained by so adjusting the legs and key C as to raise the head A to any desired height, and to diminish 75 the strain upon the key C and the pivot J, arising from actual operation of the trestle. It also shows, without lettering, a pin to hold the putlog, inserted in the pin-holes W. (Shown in Fig. 2.)

Fig. 6 is a perspective of one of the trestle-legs removed from the leg-sockets B, with triangular brace S, attached by pins, bolts, or screws n, to the foot and upper portion of the leg.

Fig. 7 is a vertical section of the trestle-head A, attached to the leg-sockets B, showing the sockets L', and showing by the dotted lines the head and leg-sockets adjusted to a different position. The drawings show the two extremes of adjustment when the parts are placed 90 upon legs of any given length.

Similar letters refer to similar parts throughout the several views, except that J refers both to the hinge-bearing of the trestle-head A and to the hinge-bearing of the leg-sockets B. 95

My invention is designed to remedy the practical difficulties and expense of constructing trestles for scaffolds for all purposes, encountered when it is found convenient or necessary to change the height or position of the same 100

in actual use. It is also designed to permit their convenient removal from one place to another without injury or rebuilding and without loss of time in so doing. It is also designed 5 to preserve the maximum strength of material composing them, and to permit trestles to be taken to pieces, stored conveniently, and again erected without any loss of material or injury to or diminution of their component parts. It 10 is also designed to admit of trestles being accurately adjusted to any desired height required for the economical performance of all kinds of labor upon them. It is also designed to permit trestles to be used upon sloping ground by 15 using legs of different lengths, as well as by adjustment. The head, leg-sockets, and key are of metal, the triangular braces of either wood or metal, and the putlog and legs of wood. Its use and operation are like those of other 20 trestles, except in the manner of erecting, taking down, and storing them. By using legs and cross-pieces (putlogs) of different lengths the trestles may be made of any desired length or height. If it is desired to make any moderate adjustment of height, it may be done by 25 unhooking the chain N, raising the key C into the top of the slot H, and increasing or diminishing the distance between the lower ends of the legs until the key will fall into the proper 30 slot, i, and again hooking the chain N. If it is desired to widen the scaffold, it may be done without even stopping the work by putting another set of trestles with a longer putlog under the one being used, adjusting the new 35 one to the same height as the old one, and putting on additional plank. By putting other trestles under a scaffold which is being used it may be safely raised or lowered without even stopping the workmen.

40 My trestle can be conveniently used in a nar-

row hall or a wide building by merely using putlogs of different lengths. It can be easily taken apart for storage or transportation, and with ordinary use will last indefinitely. The manner of its construction will be readily seen 45 by reference to the several drawings.

What I claim as my invention, and desire to secure by Letters Patent, is—

1. The combination of the key C with head A, having slot H, leg-sockets B, having slots 50 i, and the pivots J, as and for the purpose shown and described.

2. The adjustable leg-sockets B, with circular hinge-bearing J, pivoted and fitted to receive the hinge-joint J of the trestle-head A, 55 with horizontal slots i, pin-holes K, shoulders O, hollow space L', to receive the leg, hook P, and adjustable chain N, combined with the metallic trestle-head A and the metallic key C, all constructed substantially as described. 60

3. The metallic key C, in combination with the head A, having the slot H, the leg-sockets B, having the slots i, and the pivot J, said key being adapted to be entered in the slot H and engaged with the slots i before the head and 65 sockets are connected by the pin, as and for the purpose shown and described.

4. The combination of the metallic trestle-head A with the metallic key C and the adjustable leg-sockets B and the triangular-braced legs L, all constituting, essentially, the improved trestle herein described, and all constructed substantially as described, and for the 70 purpose specified.

MICHAEL MILLER.
